UNITED STATES PATENT OFFICE.

SAMUEL DARLING, OF PROVIDENCE, RHODE ISLAND.

COMPARATOR.

SPECIFICATION forming part of Letters Patent No. 292,415, dated January 22, 1884.

Application filed March 1, 1883. (No model.)

To all whom it may concern:

Be it known that I, SAMUEL DARLING, of Providence, Rhode Island, have invented a new and useful Improvement in Comparators for Comparing Measures of Length one with another; and I do hereby declare that the following, taken in connection with the drawings which accompany and form part of this specification, is a full, clear, and exact description of the invention, which will enable others skilled in the art to which it appertains to make and use the same.

The end in view by this invention is to produce an instrument with which comparisons can be made with a greater degree of accuracy and uniformity than have heretofore been made, and which the advanced state of the mechanical sciences now requires; and it consists in a comparator in which the tables that support the articles to be compared are attached to a pivoted frame, by which they can be swung back and forth under the microscopes; a comparator having above the tables and swinging frame a horizontal beam to support the microscopes, a tracer, (if one be used,) a head-rest, and any apparatus that may be required to operate the microscopes and tracer, the said beam to extend the working-length of the comparator and be supported at the ends to leave a free and open space under it for the movement of the tables and admission of light, and also to have on its side a shelf or bracket to support the ways for the microscopes, and the apparatus that may be placed upon it in the use of the comparator; a comparator having a thermometer embedded in mercury in the table or in any other part of which it is desirable to know the exact temperature; a comparator with longitudinal and transverse ways for the movements of the microscope, or with longitudinal, transverse, and vertical ways or guides by which the microscopes can be moved and adjusted; a comparator having a rest to steady the head when adjusting the microscopes; a comparator having abutting pieces arranged for comparing end-measure with line-measure, all of which I shall fully illustrate and describe in the following specification.

The great exactness with which scales are now graduated requires a correspondingly-ac-

curate instrument for comparing the length of one with another, and one part with another part of the same scale. The most important features to be obtained in a comparator are, 55 first, sufficient strength to prevent any bending, twisting, or yielding in any perceptible manner; secondly, facilities for testing the scales as rapidly and with as little manipulation as possible; and, thirdly, devices by which 60 the scales being compared can be alternately brought under the microscopes with as little motion and delay as possible, after the microscopes shall have been adjusted to the scales for the purpose of testing the accuracy of the 65 adjustment of the micrometers. But to obtain the results aimed at in this invention, with this or any comparator, the measures to be tested must be of a uniform temperature during the process, and to insure that, it will be necessary 70 that the measures to be compared and the comparator be of the same temperature throughout during the comparison. An attempt to obtain comparisons with great accuracy without having the temperature uniform would be 75 fatal to the operation. The temperature may be regulated by the use of a blower, as shown in Patent No. 227,962, May 25, 1880.

I have described and illustrated one method of constructing and operating my improved 80 comparator in the drawings, of which the upper part of Figure 1 is a full front view of the comparator, and the lower part is a longitudinal section (C D, Fig. 2) through the middle of the main frame-work. Fig. 2 is a cross- 85 section of the comparator at A B, Fig. 1, the part to the right of the cutting-plane being supposed to be removed; Fig. 3, plan or top view of the comparator, drawn to a larger scale than Figs. 1 and 2. Fig. 4 is a horizontal 90 section through E F, Fig. 1, showing the arrangement of the gearing, which will be more fully described hereinafter. The remainder 95 of the drawings illustrate details of construction and methods of operation, and will be explained in turn under those headings.

The frame of the comparator consists of four pieces of cast-iron. (Shown in Figs. 1, 2, and 3.)

G is the base, having a heavy rib, H, projecting upward on each side of its middle line and extending its whole length, as shown by

the dotted line H, Fig. 1. At the ends and on each side it has "crow-feet" I projecting, to give the machine suitable width of base to stand upon. The width of the space between the ribs H is represented by the lines J, Fig. 2, and extends outward from the lines K, Fig. 1. Between the lines K the width of this space is represented by the lines L, Fig. 2.

The two uprights M are bolted to the ends of the base G with the bolts N. These uprights are connected at their upper ends by the beam O, the same being bolted to the uprights with bolts P. At the lower edge of the connecting-beam O is a shelf, Q, which supports the microscopes P, the latter being attached to a slide or way, S.

T is a plain piece of cast-iron, attached to the base G by means of the shaft Y and boxes U V. The boxes V are bolted to the flanges W on the piece T, while the boxes U are bolted to the base G, as shown. These boxes are made in "halves" in the usual way, so they can be clamped snugly upon the shaft Y. To prevent any end motion of the hinged piece T, hardened-steel pieces X are put into the ends of the shaft Y, and abutting pieces Z are attached to bed G in boxes Z₁, and held against the shaft by set-screws A₁.

To the swinging piece T are attached the head-pieces C₁ and D₁, upon which are fitted the sliding tables E₁ and F₁. Upon these tables rest the standards or scales G₁ and H₁, while being compared one with another. The head-piece G₁ is bolted firmly to the swinging piece T, and the head-piece D₁ has a vertical adjustment, which will be understood on reference to Figs. 1, 2, 4, 10, and 11. It is attached to T by means of four bolts, J₁, which pass through slotted holes in D₁ (the slots being sufficiently long to allow the required vertical adjustment) and are screwed into T. J₁, Fig. 4, are worm-wheels passing through and their hubs fitting into slots in D₁, more plainly shown in Figs. 10 and 11. Right-handed screws K₁ are fixed into the worm-wheels J₁, and screw into the bolt-studs L₁, which are fitted into T and bolted to C₁. Cavities M₁, Fig. 11, are cored into D₁, as shown, so as to allow D₁ to move up and down the required

distance without striking the studs L₁. Two shafts, N₁ and O₁, are fixed to D₁ by means of the bearings P₁. To these shafts are fixed the hand-wheels Q₁, the miter-wheels R₁, and a right-hand worm, S₁, and a left-hand worm, T₁, meshing into the worm-wheels J₁. The miter-wheel U₁ is fixed into the hand-wheel V₁, and is supported by the stud W₁. X₁ is a link, which is thicker at one end than the other, and is suspended from the stud W₁ between the hub of the hand-wheel V₁ and the nut Y₁. By turning the hand-wheel V₁, motion will be imparted to both the shafts N₁ and O₁, and both ends of the head-piece D₁ will be raised or lowered simultaneously and alike.

By turning the link X₁ over so it will be suspended by its thin end, the miter-wheel U₁ may be drawn out and disengaged from the

wheels R₁, after which either end of the head-piece D₁ may be raised or lowered slightly and independently of each other by turning either of the hand-wheels Q₁.

Fig. 17 shows more plainly the manner in which the tables E₁ and F₁ are fitted and fastened to the head-piece C₁ and D₁. A "half-dovetail" is formed at Z₁, and against this the tables E₁ and F₁ are held by the clamps A₂ and bolts B₂ and C₂.

The bolt B₂ is provided with a "tail-nut," D₂, so it can be conveniently tightened from the front side of the comparator—the side to the left in Fig. 2. The tables E₁ and F₁ are so fitted as to have their upper surfaces inclined sufficiently to bring them perpendicular to the axis of the microscopes when brought directly under the latter.

The rear table, E₁, is provided with a screw, E₂, and hand-wheel F₂, (shown in section in Fig. 1,) by means of which it may be adjusted endwise. The means for adjusting the front table, F₁, may be seen by referring to Figs. 1, 2, 3, 5, 6, and 7, the same being provided with

two racks, G₂, fastened to the bottom side of the table F₁, and pinions H₂, connected with the hand-wheels I₂ and J₂, and fitted into the head-piece D₁. For delicate adjustments the hand-wheel J₂ has a V-groove turned into it, and into this is fitted a slide, K₂, Fig. 6, which

may be adjusted to any part of the circumference of the wheel J₂. Into this slide K₂ is fitted a lever, L₂, of considerable length, by means of which the table F₁ may be moved very slowly. The stud M₂ and clamp N₂ serve as a fastening to hold the table F₁ in a definite position.

On the right-hand end of the head-piece D₁ is fitted a stop, O₂, which limits the motion of the table F₁. This stop has a tongue, P₂, on the lower side, fitting into a corresponding groove in the casting D₁. There are a number of these grooves at regular intervals, so the stop O₂ can be moved to different positions, and thus regulate, in connection with the set-screw Q₂, the amount of motion of the table F₁.

On the left hand a stop, R₂, is bolted to the casting D₁, and provided with the set-screw Q₂ for adjustment. S₂, T₂, and U₂ are steel plugs set into the table F₁ and the stop O₂, to form hard abutting surfaces. The point of the set-screw Q₂ is also hardened. V₂ is a clamp-screw for the purpose of tightening the screw Q₂.

In using the comparator it will be necessary to swing the central piece, T, upon its pivots V U, in order to bring the tables E₁ and F₁ and scales or standards H₁ and G₁ alternately under the microscopes R. To accomplish this, a hand-wheel, W₂, is suitably fastened to the upright M on the left, Fig. 1, substantially as shown.

A link, X₂, is fastened at one end with a hinge-joint to castings T and C₁, and at the other end it is attached to a slide-block, Y₂, which is adjustable diametrically in reference to the wheel W₂, thus allowing a variation in the stroke or throw of the swinging parts. The clamp Z₂ serves to clamp the hand-wheel W₂ in any desired position. For this

purpose the clamp Z_2 is provided with an index-point, A_3 , and the rim of the wheel is graduated on the side, as shown in Fig. 2. The microscopes R are mounted upon suitable frames, F_3 , which are clamped to the slide S by means of set-screws G_3 .

Fig. 9 is a partial side view of the tables E_1 and the standard G_1 , showing the manner of inserting thermometers H_3 , by means of which the temperature of the metal may be read at any time. I_3 is a glass inclosing the thermometer in the cavity J_3 . The cavity J_3 is partially filled with mercury surrounding the bulb of the thermometer to readily transmit any variation of temperature from the metal to the thermometer.

Fig. 8 is a top view of the standard G_1 , Fig. 9.

Fig. 18 is a top view of a microscope and slide. F_3 is a sliding frame, attached to the slide S . 7 is a cross-slide attached to F_3 and clamped by screw 3 . 8 is a vertical slide, and is attached to slide 7 . It is adjusted by screw 6 , while 4 and 5 are screws that tighten slide 8 ; G_3 , screws that hold slide F_3 firmly to slide or way S .

Fig. 19 is a cross-vertical section through A B, Fig. 18. 14 is the micrometer-screw, and 2 is the clamp-screw, which secures the microscope to slide 8 .

Fig. 20 is a rear section through line C D, Fig. 19. It will be seen that by these slides and ways the microscopes can be adjusted vertically, longitudinally, and transversely with great facility.

That the comparator may stop accurately at the same point each time it is swung, stops B_3 , Fig. 2, are put into the uprights M , at each end of the machine, and steel pieces C_3 bolted to the frame, to form true and firm bearing-surfaces to come against the stops. The comparator is swung back and forth by wheel W , and brought gently against the stops B_3 . When the comparator is swung past the center, it will have a tendency to move itself, and, should it be required, springs may be attached to the heads M , coming in contact with the comparator, and so arranged that it will be nearly balanced in all positions. However, it will be better for it to have sufficient tendency to move itself to insure its coming against the stops B_3 . The comparator being swung by a slow crank motion, and coming against the stops at the dead centers, there will be no perceptible shock when it comes in contact with the stops.

To explain the operation of this comparator, a metallic bar, G_1 , representing a standard yard-measure, is clamped or otherwise properly secured to table E_1 , Figs. 2 and 15. This bar has two lines, A_6 and A_7 , traced upon its surface, one near each end, the space between the lines being a standard yard. A bar, H_1 , to be compared to bar G_1 , is secured to table F_1 in a similar manner, having lines B_6 and B_7 near the ends the same as bar G_1 , the distance between which is intended also to be a standard yard. The bars having been thus placed

and secured in position, the tables are swung forward and the standard-bar G_1 is brought under the micrometer-microscopes R and R_6 , Fig. 14. Microscope R is placed over line A_6 , and microscope R_6 over line A_7 , and firmly clamped to slides S , Fig. 2. Then, after adjusting the cross-hairs of the micrometers to their respective lines, the tables are swung back and the bar H_1 brought under the microscopes, Fig. 16, and by means of the vertical adjustment of the head D the surface of the bar H_1 is brought up to the face of the microscopes, and by means of the end adjustment of the table F_1 , or by moving the bar H_1 , line B_6 is adjusted to the cross-hairs of microscope R , Fig. 16. After being thus arranged, the bars should be alternately brought under the microscopes several times and critically examined to guard against errors in the adjustment of the micrometers. The process being thus completed, microscope R_6 will show how the lengths of the two bars agree. To obtain the best results, the two bars should be of the same kind of metal, and they must be of a uniform temperature during the process of comparing; and if the bars be of different kinds of metal the exact degree of temperature must be known. An effective method of regulating the temperature was referred to above.

To test the uniformity of the graduation of a scale—say three feet long, more or less—first compare the feet together, then one-half of each foot (six inches) with the other half; then one-half of each six inches (three inches) with the other half; and as two microscopes cannot be placed much nearer together than three inches, the inches and parts of inches can be tested, as described below. In comparing the feet, half-feet, and quarters of feet together, as above indicated, the scale can be moved under the microscopes, or the microscopes may be clamped firmly together and moved over the scale; but the former method is considered preferable when the scale can be conveniently moved.

The following is one method of testing the smallest subdivisions of a scale. Fig. 5 is a top view of table F_1 , Fig. 2, and Fig. 6 is a front elevation of the same. A bar of metal, M_3 , having two lines, N_3 and O_3 , at a distance apart nearly the same as the subdivisions to be tested, is firmly fastened on the left end of table F_1 . The scale K_3 to be tested is clamped upon the table F_1 by clamps L_3 , or secured in any of the known ways of doing such work. By means of screw Q_2 and stop U_2 the motion of the table F_1 is limited, for convenience, to the distance between marks N_3 and O_3 on bar M_3 .

To compare the space on the scale K_3 from 0 to 1, to the space from O_3 to N_3 on bar M_3 , the table F_1 is moved to the left against the stop-screw Q_2 . Microscope Q_3 is adjusted to line 0 on scale K_3 , and microscope P_3 to line O_3 on bar M_3 ; then the table is moved to the right until microscope P_3 coincides with line N_3 ; and after moving the table back and forth several times and critically noting the adjust-

ment of the micrometers to avoid errors, the difference between the length of the two spaces, if any, will be indicated by microscope Q_3 ; then the table F_1 is moved to the left, as before, against set-screw Q_2 , and microscope Q_3 is moved over and adjusted to mark 1, and microscope P_2 is adjusted to line O_2 ; then the table is moved to the right until microscope P_2 shall again coincide with line N_2 ; and after moving back and forth several times, as before, to test the accuracy of the adjustment of the micrometers, the reading of microscope Q_2 over line 2 on the scale, will show how space from 1 to 2 on scale K_2 agrees with space from 15 O_2 to N_2 , and so on until all the spaces on K_2 shall have been tested. The screw-stops Q_2 and U_2 need not be depended upon for accuracy, but if they are made sufficiently strong there is no reason why they should not be. They 20 should be made so as not to yield perceptibly to any pressure brought against them. Table F_1 is moved up to stop U_2 by lever L_2 , which is made of a size that will bend sufficiently easy, and is so arranged that table F_1 will 25 come in contact with stop U_2 a little before the lever touches the rest M_2 , so that when the lever is brought down to the rest and secured by clamp N_2 it will be bent a little, as shown by the dotted lines. This spring of the lever 30 serves to keep the table against stop U_2 always with the same force. The table is held against set-screw Q_2 in a similar manner and one lever may be used for both wheels I_2 and J_2 . It will be seen that more than one microscope could 35 be used to advantage on scale K_2 to test more than one space at a time.

One method of comparing end-measure with line-measure with this comparator is shown in Figs. 2, 12, and 13. The standard bar G_1 , having lines C_4 and D_4 , is secured to table E_1 by clamps Z_3 and Z_4 . Upon the front table, F_1 , is rigidly attached an abutting bar, R_3 . S_3 is a similar bar, placed against R_3 , and held in place by springs U_3 and V_3 , pin J_3 , holding bar W_3 45 in position. T_3 is a wooden handle, by which the bar S_3 is moved to prevent the warmth of the hand from affecting its temperature. X_3 is an end-measure to be compared to the line-measure standard G_1 , and is laid loosely upon 50 the table F_1 . The comparator is then swung forward by wheel W_2 , and the microscopes E_4 and F_4 are adjusted to the lines C_4 and D_4 on the standard G_1 . The comparator is then 55 swung back, and, by means of vertical adjustment of head D_1 and the longitudinal adjustment of table F_1 , mark H_4 on bar S_3 is adjusted to microscope E_4 , and microscope B_4 is adjusted to mark G_1 on bar R_3 . Then the comparator should be swung back and forth several 60 times and the adjustment of cross-hairs critically examined to prevent errors. The comparator being left forward for convenience, the bars S_3 and W_3 are removed and the end-measure X_3 placed carefully against bar R_3 , Fig. 13, and secured in position by springs Y_3 . Bar S_3 is then placed against end-measure X_3 , and held by springs U_3 and V_3 . R_3 must be so

secured to the table F_1 that no pressure that will be brought against it will move it. Great pains must be taken to have the abutting ends 70 free from dust and lint, &c., before placing them together, which will need to be done with the utmost care. The end-measure having been thus carefully put in position, the comparator is swung back and marks H_4 and G_1 brought under microscopes F_4 and B_4 , and if line H_4 coincides with microscope F_4 , and line 75 G_1 with microscope B_4 , the end-measure X_3 agrees with standard G_1 . The extra microscope B_4 is used to detect any longitudinal 80 movement of the bar R_3 or of the comparator, should such an accident happen. To guard against slight errors before considering the process completed, the comparator should be moved back and forth several times and the 85 microscopes examined critically each time.

End-measure can be compared with line-measure with a comparator having but one table, as shown by the following brief description, viz: A line-measure, G_1 , an end-measure 90 X_3 , a fixed abutting bar, R_3 , and a movable abutting bar, S_3 , are placed on a table, as shown in Fig. 20^a. Bar S_3 is placed and held against bar R_3 . Microscope E_4 is placed and firmly held over and adjusted to line H_4 . (Microscope B_4 may be set over and adjusted to line G_1 at the option of the operator.) Then measures G_1 and X_3 and bar S_3 are arranged as shown in Fig. 21. Line C_4 is adjusted to microscope E_4 , and microscope F_4 is set over 100 and adjusted to line D_4 . Then the articles are arranged, as shown in Fig. 22, when microscope F_4 will show the comparative lengths of the two measures. When short measures—say 105 two feet and less—are to be compared, the abutting bar S_3 and microscope E_4 can be dispensed with, as shown in Figs. 23 and 24, the line-measure G_1 , being made to perform the function of bar S_3 in addition to its own. Being arranged as shown in Fig. 23, line-measure 110 G_1 is placed and held in contact with bar R_3 , and microscope F_4 is placed over and adjusted to line D_4 . Then line-measure G_1 is run back and end-measure X_3 is placed between it and bar R_3 , as shown in Fig. 24, and line-measure 115 G_1 is pressed against bar X_3 sufficiently to hold the abutting surfaces in contact when microscope F_4 , over line C_4 , will show how the measures agree, the line-measure G_1 having been 120 run back the exact length of end-measure X_3 .

In testing measures of length, the most essential and, perhaps, the most difficult part of the operation is to bring the articles to be tested to a uniform temperature, and keep them so during the process; and when two kinds of 125 metal are compared together, it is necessary to know the exact degree at which they are tested. The usual method of laying a thermometer on the scale which is to be tested, or on the table with it, is not sufficiently reliable; therefore I embed a thermometer in the scale when it is thick enough, and also in the table of the comparator, Figs. 8 and 9, for the temperature of the table affects the scale, which 130

rests upon it, and nearly controls the temperature when the scale is thin. The thermometer will need to be as small as possible when inserted into the table or scale, but it 5 may be made of common size, and the bulb only inserted, as shown in Fig. 9, in which case a hole, D_6 , is drilled in the piece and filled with mercury, and the bulb of thermometer set in the hole, the latter being packed around the thermometer to prevent the atmospheric 10 air from affecting the mercury; and for that purpose a rubber ring, Z_6 , may be put around the thermometer, just filling the top of the hole. When the thermometer is taken out, 15 the hole may be stopped with a rubber plug, H_6 , or the mercury can be taken out. In a heavy standard, doubtless, it would be more convenient to have the thermometer embedded in it. It is obvious that the insertion of 20 a thermometer into many other kinds of machinery would be of great advantage, as it would always indicate the exact temperature of the piece it is in.

In testing end-measures, the standard line- 25 measure may be the movable abutting bar S_3 for short measures; but for measures of three feet or more it would require too long a comparator for convenience and economy, and it would be better to have the standard on a 30 separate bar, as shown and described above. With the standard graduated on the movable abutting bar, comparisons can be made with one microscope when a detective-microscope, B_4 , is not used. Referring to the swinging of 35 the comparator-tables, it will be seen that the accuracy of the comparisons will not depend upon the accuracy with which the tables are swung back and forth. As there are always two microscopes used when the tables are 40 swung, any movement longitudinally would be detected.

The tracer referred to above is not a part 45 of the comparator, but is a small instrument for copying graduated measures, and is well known to all who are familiar with the art. It is constructed in various ways, has a cutter, and means for holding and operating the same, and generally carries a microscope. In using 50 a tracer with my comparator, it would be attached to slide S on beam O , on which it would be operated. The head-rest Y_5 is a horizontal shelf, as shown in the drawings, but may be made in any convenient form for the operator to rest his head upon when looking through 55 the microscopes. This support or head-rest may be a part of the beam O , or a separate piece, and fastened to it, and it may be made vertically adjustable. I preferably make the height of said rest so as to bring the head of 60 the operator in the right position when his head rests upon his hand and his hand upon the shelf O . I prefer to rest my forehead on my left fist, the latter resting on the head-rest, leaving the right hand free for operating the 65 micrometer of the microscope. The benefit of this device is obvious, considering the great difficulty of holding the head sufficiently steady

when making observations with microscopes of high power.

Having fully described my improvement, 70 what I claim, and desire to secure by Letters Patent, is—

1. For testing measures of length, a comparator having, in combination with microscopes, separate tables or supports for said measures 75 fixed to a swinging frame, substantially as described.

2. A comparator having, in combination with a table or tables, microscopes and a beam supporting the microscopes, a tracer, and 80 head-rest, said beam being held by its ends and elevated above the tables, leaving the space under it open for the moving back and forth of the tables under said beam and the admission of light, substantially as described. 85

3. A comparator having, in combination, a table adjustable longitudinally, a metal bar, M_5 , stops O_2 and Q_2 , to limit its motion, and two or more microscopes, substantially as described. 90

4. A comparator having, in combination, microscopes, table F_1 , and means for adjusting said table longitudinally, including lever L_1 , and stop-rest M_5 , substantially as described.

5. A metallic bar or body having in it a 95 mercury-well, and a thermometer embedded in said well, substantially as described, and for the purpose set forth.

6. For comparing measures of length, a comparator having a table or support for the 100 articles to be compared, said table having in it a mercury-well, and a thermometer embedded in the well, substantially as described, and for the purpose set forth.

7. For comparing measures of length, a 105 comparator having, in combination, a table or support for the measures, one or more microscopes, a guide or slide, S , running nearly parallel with the table, a vertical guide, 8 , and a transverse guide or slide, 7 , by means of which 110 the microscopes can be moved parallel, transversely, and vertically to the table, for the purpose of adjusting the cross-hairs of the microscopes to the lines of the measures.

8. The method of comparing lineal end-measure with lineal line-measure, which is as follows: first, bringing into end contact with a fixed bar a movable bar having traced thereon a fine line; second, adjusting the cross-hairs of a microscope to this line; third, substituting for the 120 movable bar a line-measure, and adjusting one of the lines thereon, to coincide with the microscope cross-hairs; fourth, adjusting the cross-hairs of a second microscope to the other line of the line-measure; fifth, substituting for the line-measure an end-measure, abutting it against the fixed bar; sixth, abutting the movable bar against the end of the end-measure; seventh, observing the line on the movable bar through the second microscope, and noting 125 the amount of divergence, if any, of the line from the cross-hairs of the microscope.

9. The following method of comparing lineal end-measure with lineal line-measure:

first, abutting the line-measure against a fixed bar; second, adjusting a microscope to that line of the line-measure which is farthest from the fixed bar; third, inserting between the fixed bar and the line-measure an end-measure; fourth, observing through the microscope that line on the line-measure which is nearest to the fixed bar, and noting the divergence, if any, of the line from the cross-hairs of the microscope.

10. For comparing end-measure with line-measure, a comparator having, in combination, a table or support for the measures, two or more microscopes, and two abutting bars, substantially as described.

11. For comparing end-measure with line-measure, a comparator having, in combination, a table or support for the articles to be compared, one or more microscopes, and two

abutting bars, one of the abutting bars to be provided with the line-measure, substantially as described.

12. For comparing end-measure with line-measure, a comparator having a table or support for the measures, two abutting bars, and one or more detective microscopes, substantially as described, and for the purpose set forth.

13. A comparator having, in combination, one or more tables or supports for the articles to be compared, one or more microscopes, and a head-rest, substantially as described, and for the purpose set forth.

SAML. DARLING.
